UNITED STATES PATENT OFFICE.

ISAAC B. POTTS, OF COLUMBUS, OHIO.

IMPROVEMENT IN PAVEMENTS.

Specification forming part of Letters Patent No. 172,167, dated January 11, 1876; application filed December 31, 1874.

To all whom it may concern:

Be it known that I, ISAAC B. POTTS, of Columbus, in Franklin county, and State of Ohio, have invented an Improvement in Pavements, of which the following is a specification:

This invention is designed to secure a more permanent roadway of concrete or asphalt surface than has heretofore been obtained; and it consists in a bed of sand rounded from curb to curb, on which a course of stone blocks are set edgewise and parallel with the line of road, the interstices being filled with a suitable grouting, to which the surfacing-course of asphalt, concrete, or other suitable composition will adhere, as hereinafter more fully described.

The accompanying drawing represents, in perspective, a vertical section of my pavement on a line transverse to the length of the roadway.

In constructing this roadway, I first grade the street to a proper depth below the upper edge of the curbs A, then surface it with sand or gravel B, rounded to the desired profile, to form a center, as it were, on which to build an arch formed by setting a course of blocks of stone, C, arranged edgewise and parallel with the line of road, so as to form a continuous arch between the curbs A. The crevices between the blocks C, and irregularities on their surface, are then to be filled with tar, asphalt, or other suitable grouting, to consolidate the arch, and form an approximately level surface. The substructure thus formed is then to be surfaced with a finishing-course, D, of concrete, asphalt, or other suitable composition best adapted to the climate and locality in which

it is to be used, and that will adhere to or combine with the grouting of the substructure.

By thus building the substructure, it will be evident that the composition surface will not be as liable to depression, and consequent cracking and destruction, as when laid on a rubble or broken-stone foundation, which has no supporting quality in itself, being sustained entirely by the earth and sand beneath.

I am aware that a cobble-stone pavement, set in the ordinary manner, and having the interstices between the stones filled with grouting of asphalt or concrete to render it impervious to moisture, has been devised before; but this does not constitute what is known as a concrete pavement; neither can a substructure constructed of cobble-stones possess the property of an arch, although it may be in that form. This, therefore, I do not claim.

Having thus described my invention, its construction, and advantages, what I claim, and desire to secure by Letters Patent, is—

A roadway constructed with a bed of sand rounded from curb to curb to the desired profile, and a course of stone blocks set edgewise and parallel with the line of road, so as to form an arch between the curbs, in combination with a filling and leveling course of tar, asphalt, or other suitable grouting, and a surfacing-course of concrete or other suitable composition, substantially as specified.

ISAAC B. POTTS.
